R. J. FAIRCHILD

POWER PUMP

Filed June 4, 1921

Patented Apr. 24, 1923.

1,452,963

UNITED STATES PATENT OFFICE.

ROLAND J. FAIRCHILD, OF KALAMAZOO, MICHIGAN, ASSIGNOR TO NATIONAL WATER LIFT CO., OF KALAMAZOO, MICHIGAN.

POWER PUMP.

Application filed June 4, 1921. Serial No. 474,951.

To all whom it may concern:

Be it known that I, ROLAND J. FAIRCHILD, a citizen of the United States, residing at the city and county of Kalamazoo, State 5 of Michigan, have invented certain new and useful Improvements in Power Pumps, of which the following is a specification.

This invention relates to improvements in power pumps.

10 The main objects of this invention are:

First, to provide an improved pump driven by an electric motor which is well adapted for use in residences for pumping cistern water and is very compact and simple 15 in structure.

Second, to provide an improved pump having these advantages in which a small motor may be employed and at the same time pump the water against a considerable pressure.

20 Further objects, and objects relating to structural details, will definitely appear from the detailed description to follow.

I accomplish the objects of my invention 25 by the devices and means described in the following specification. The invention is clearly defined and pointed out in the claims.

A structure which is a preferred embodiment of my invention is clearly illustrated 30 in the accompanying drawing, forming a part of this specification, in which:

Fig. I is a side elevation of my improved pump, the pan which I preferably provide 35 in this connection being partially broken away.

Fig. II is a detail view partially in vertical longitudinal section with the motor omitted, the section being on a line corresponding to line 2—2 of Fig. III.

Fig. III is a transverse section on a line corresponding to line 3—3 of Fig. II.

In the drawing similar reference characters refer to similar parts throughout the 45 several views, and the sectional views are taken looking in the direction of the little arrows at the ends of the section lines.

Referring to the drawing, I provide a pump cylinder 1 having a piston 2 and piston 50 rod 3. These parts are shown conventionally.

I also provide a gear box 4 having a removable side plate 5.

On the side opposite the removable side 55 plate the gear box is provided with an in-

wardly projecting bearing 6 having a bushing 7 therein for the spindle 8 of the worm gear 9. A removable cap 10 is provided for the outer end of the bearing, thus affording access for assembling and adjusting the 60 parts. Above this bearing is an opening 11 provided with a closure 12 through which lubricant may be introduced. The gear box is provided with a cylindrical worm housing extension 13 at its top and a connecting 65 rod and crosshead extension 14 at the front. The gear box also has base members or feet 15. On the extension 14 is a seat 16 for the electric motor 17. The shaft 18 of this motor is aligned with and connected to the 70 shaft of the worm 19 by means of the joint 20, the worm being supported in the worm housing extension 13 so as to mesh with the worm gear 9.

A base 21 is provided for the pump cylinder 1, the base having a yoke 22 with a head 23 for one end of the cylinder and a head 24 for the extension 14 of the gear box, the extension being bolted to this 75 head 24.

Pinion rod packings 25 are provided for the heads 23 and 24. A crosshead 26 is mounted in the extension 14, the connecting rod 27 and the pinion rod being connected to this crosshead as shown in Fig. II.

By thus forming and arranging the parts, I provide a structure which is very compact. The moving parts are effectively supported in proper relation and properly aligned and a comparatively small motor or 90 motor of small horse power may be employed.

Having thus described my invention, what I claim as new and desire to secure by Letters Patent is:

1. In a power pump, the combination with a cylinder, piston, and a piston rod, of a gear box provided with a base and having a removable side plate and an inwardly projecting bearing on its wall opposite said 100 side plate, there being a removable cap for the outer end of said bearing, said gear box also having a worm housing extension at its top, and a connecting rod and crosshead extension at the front, a base for said cylinder provided with a yoke having a cylinder head at one end and a head for said crosshead extension at the other, said heads being provided with packings for said piston rod, a worm gear mounted in 110

- said bearing in said gear box, a connecting rod, a crosshead to which said piston and connecting rods are connected sliding in said extension, a motor mounted on said crosshead and connecting rod extension, and a driving worm to which the motor shaft is connected mounted in said worm extension of said gear box to coact with said worm gear.
2. In a power pump, the combination with a cylinder, piston, and a piston rod, of a gear box provided with a base and having a connecting rod and crosshead extension at the front, a base for said cylinder provided with a yoke having a cylinder head at one end and a head for said crosshead extension at the other, said heads being provided with packings for said piston rod, a worm gear mounted in said gear box, a connecting rod, a crosshead to which said piston and connecting rods are connected sliding in said extension, a motor mounted on said crosshead and connecting rod extension, and a driving worm to which the motor shaft is connected mounted in said gear box to coact with said worm gear.
3. In a power pump, the combination with a cylinder, piston, and a piston rod, of a gear box having a removable side plate and an inwardly projecting bearing on its wall opposite said side plate, there being a removable cap for the outer end of said bearing, said gear box also having a worm housing extension at its top, and a connecting rod and crosshead extension at the front, a worm gear mounted in said bearing in said gear box, a connecting rod, a crosshead to which said piston and connecting rods are connected sliding in said extension, a motor mounted on said crosshead connecting rod extension, and a driving worm to which the motor shaft is connected mounted in said worm extension of said gear box to coact with said worm gear.
4. In a power pump, the combination with a cylinder, piston, and a piston rod, of a gear box having an extension at the front, a base for said cylinder provided with a yoke having a cylinder head at one end and a head for said gear box extension at the other, said heads being provided with packings for said piston rod, a worm gear mounted in said gear box, a connecting rod, a crosshead to which said piston and connecting rods are connected sliding in said extension, a motor mounted on said gear box extension, and a driving worm to which the motor shaft is connected mounted in said gear box to coact with said worm gear.

In witness whereof, I have hereunto set my hand and seal.

ROLAND J. FAIRCHILD. [L. S.]
